(57) **CLAIM**

We claim the ornamental design for an air conditioner, as shown and described.

DESCRIPTION

FIG. 1 is a front perspective view of an air conditioner showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is an inverted front perspective view thereof;

FIG. 9 is another inverted front perspective view thereof;

FIG. 10 is an enlarged view of the encircled portion in FIG. 1;

FIG. 11 is an enlarged view of the encircled portion 11 in FIG. 2;

FIG. 12 is an enlarged view of the encircled portion 12 in FIG. 2;

FIG. 13 is an enlarged view of the encircled portion in FIG. 3;

FIG. 14 is an enlarged view of the encircled portion in FIG. 4;

FIG. 15 is an enlarged view of the encircled portion 15 in FIG. 8;

FIG. 16 is an enlarged view of the encircled portion 16 in FIG. 8;

FIG. 17 is an enlarged view of the encircled portion 17 in FIG. 9;

(Continued)

FIG. 18 is an enlarged view of the encircled portion 18 in FIG. 9; and,
 FIG. 19 is an enlarged view of the encircled portion 19 in FIG. 9.

The evenly-dashed broken lines in the figures depict portions of the air conditioner which form no part of the claimed design.

The dot-dot-dash broken lines encircling portions of the claimed design that are illustrated in enlargements form no part of the claimed design.
